FARM BUILDING

James E. Lang, Cudahy, Wis.

Application January 22, 1949, Serial No. 401

Term of patent 7 years

(Cl. D13—1)

To all whom it may concern:

Be it known that I, James E. Lang, citizen of the United States and resident of Cudahy, in the county of Milwaukee and State of Wisconsin, have invented a new, original, and ornamental Design for a Farm Building, of which the following is a specification, reference being had to the accompanying drawings, forming part thereof.

Figure 1 is a front perspective view of a farm building, showing my new design; and

Figure 2 is a rear perspective view thereof.

I claim:

The ornamental design for a farm building, as shown.

JAMES E. LANG.
